UNITED STATES PATENT OFFICE.

CHARLES T. WESTLAKE, OF ST. LOUIS, MISSOURI, ASSIGNOR TO SWING ROLLING TRUCK CO., OF ST. LOUIS, MISSOURI, A CORPORATION OF DELAWARE.

CAR-TRUCK.

1,079,458.

Specification of Letters Patent. Patented Nov. 25, 1913.

Application filed January 20, 1913. Serial No. 743,087.

To all whom it may concern:

Be it known that I, CHARLES T. WESTLAKE, a citizen of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a sectional view taken transversely through a car truck of my improved construction at a point adjacent to the bolster and spring plank, and showing the rolling supports for the bolster, as contemplated by my invention. Fig. 2 is a sectional view similar to Fig. 1, and showing the bolster and rolling supports in the positions they assume when the bolster is shifted or swung laterally with respect to the truck frame. Fig. 3 is a horizontal section taken approximately on the line 3—3 of Fig. 1.

My invention relates generally to improvements in railway car trucks, and more particularly to the supporting means for the end portions of the truck bolster, which supporting means, in the form of rolling bearings, permits the bolster to move or swing laterally with respect to the truck frame and at the same time elevating one end of the bolster.

The feature of a lateral or swing-motion car truck, and which gives it its name, is the provision therein for a certain amount of lateral swing or movement of the truck bolster relative to the truck frame, and thus, under normal conditions and upon straight track the bolster is maintained in a substantially horizontal plane, and when turning a curve at other than very low speed, the centrifugal force of the car body transmitted to the bolster causes the same to swing or shift laterally of the truck frame centrifugally of the track curve.

It is the usual practice in lateral or swing-motion trucks to utilize pairs of swing hangers, the members of which pairs converge alike toward their upper ends, and such arrangement produces a horizontal force at the lower end of each hanger, and this force, being normally equal, will balance and maintain the bolster in a horizontal plane.

Any external force applied horizontally to the weight carried by the swing hangers will cause said weight to swing laterally, and during such swinging movement the weight will be constrained to travel in a curved path and at the same time said weight which is represented by the car body will partially rotate about an imaginary axis. This arrangement of swing hangers has been found very desirable and advantageous in car trucks, and it is the principal object of my invention to accomplish the same result by the use of rolling bearings beneath the ends of the bolster, which arrangement effects a material reduction in cost of application and maintenance in number of parts and in weight.

A further object of my invention is to provide bearing surfaces or seats of proper contour for the rolling bearings beneath the ends of the bolster so that when said bolster moves laterally in either direction the movement attained by the use of swing hangers will be reproduced and the car body in traveling through a curved path is raised at one side more than the other, and at the same time said car body is caused to rock or to partially rotate about an imaginary axis.

To the above purposes my invention consists in certain novel features of construction and arrangement of parts hereinafter more fully described and claimed.

Referring by numerals to the accompanying drawings which illustrate a simple construction and arrangement for carrying out my invention, 1 designates the truck bolster, 2 the spring plank, 3 the elliptic springs supported by said spring plank and 4 the roller bearing plates which are supported by said springs 3 and upon which the rollers engage or bear. The tops of the plates 4 are provided with bearing surfaces or seats 5 which are preferably curved throughout their length and preferably rising gradually from the inner ends of said plates to the outer ends thereof.

Fixed to the undersides of the end portions of the bolster 1 are bearing plates 6 which are practically the reverse of the plates 4, and the undersides 7 of these plates 6 are gradually curved downward from their outer ends toward their inner ends, thus a pair of oppositely arranged, curved bearing surfaces are provided on the

adjacent faces of the plates 4 and 6, and interposed between these plates and engaging on said curved bearing surfaces are rollers 8, preferably constructed of hardened metal.

5. If desired the ends of the plates 4 and 6 may be provided with flanges or shoulders to prevent endwise movement of the rollers during their rolling movement upon the curved bearing surfaces, and the plates 6

10 may be part of the bolster 1. With the parts in normal positions, as shown in Fig. 1, and with the rollers at central positions between the ends of the plates 4 and 6, the bolster is maintained in practically a horizontal plane, 15 and by arrangement of the curved bearing faces with respect to the interposed rollers and with respect to each other, the bolster will tend to retain its horizontal position while the truck is traveling on straight track.

20 In my improved construction it will be noted that the curved or concave roller seats or bearing faces of the plates 4 and 6 are arranged so that straight lines passing through the centers of the interposed rollers

25 and the points of contact between said rollers and the roller seats will converge upward in all positions of the rollers. Thus, I obtain in rolling supports the same effect as is obtained by the use of converging swing 30 hangers.

When the bolster is moved in the direction indicated by the arrow in Fig. 1, as a result of centrifugal force developed by the car rounding a curve at comparatively high 35 speed, the plates 6 carried by the bolster will ride upon the rollers toward the right, and said rollers will be caused to move in like direction upon the curved bearing surfaces of the plates 4.

40 By the arrangement of the curved bearing surfaces on the plates 4 and 6 on the right hand side of the truck the right hand end of the bolster will be elevated, as shown in Fig. 2, while the opposite or left hand end 45 will be lowered, due to the fact that the left hand roller has traveled to the lowermost or deepest portions of the bearing surfaces on the plates 4 and 6 on the left hand side of the truck. As a result, the car body supported by the bolster moves through a 50 curved path, and at the same time is caused to partially rotate about an imaginary axis.

55 During the movements just described the roller on the right hand side of the truck encounters considerable resistance by reason of its bearing against the higher portions of the curved bearing surfaces, and thus the centrifugal force of the car body transmitted to the bolster is absorbed or counteracted 60 and utilized to maintain equilibrium of the car body in its passage around curves at comparatively high speed.

By my improved construction the action and desirable results obtained by the use of

swing hangers are reproduced, and by the use of rolling supports a considerable amount of friction is eliminated and a considerable saving is effected in weight, number of parts, original cost and repairs.

It will be readily understood that minor 70 changes in the size, form and construction of the various parts of my improved car truck can be made and substituted for those herein shown and described without departing from the spirit of my invention, the scope 75 of which is set forth in the appended claims.

I claim:

1. A car having a rolling body support operating on surfaces formed and arranged so that, when the car body moves laterally, 80 it is caused to travel in a curved path and to also partially rotate about an imaginary axis.

2. A car having a rolling body support operating on surfaces formed and arranged 85 so that when the car body is moved laterally, one side thereof is elevated and the other side is lowered.

3. In a car truck, a bolster, rolling supports beneath said bolster, and bearing surfaces for said rolling supports, which surfaces are arranged to elevate one end of said bolster and to lower the opposite end when the bolster is shifted laterally with respect 90 to the truck.

4. In car construction, a lateral motion device comprising rollers and curved roller seats arranged so that straight lines passing through the centers of the rollers and points of contact between the rollers and seats converge upward in all positions of the rollers.

5. In a car truck, a bolster having curved roller seats, rollers engaging said roller seats for supporting the bolster; said roller seats being formed so that straight lines passing 105 through the centers of the rollers and points of contact between the rollers and seats converge upwardly in all positions of said rollers.

6. In a car truck, a bolster provided with 110 curved bearing faces, supporting rollers which engage the bearing faces on said bolster, and roller supporting members provided with curved roller seats upon which the rollers engage, which roller seats and 115 interposed rollers are arranged so that straight lines passing through the centers of the rollers and points of contact between the rollers and seats converge upward in all positions of the rollers.

7. In car construction, a lateral motion device comprising rollers and roller seats arranged so that the car body when moved laterally from its normal position will be constrained to travel in a curved path and 125 to partially rotate about an imaginary axis.

8. In a car truck the combination with a bolster, of supporting means for each end

thereof which supporting means comprises pairs of plates and rollers interposed between the plates of each pair, said plates having curved roller seats arranged so that 5 when the car body is moved laterally from its normal position it will be constrained to travel in a curved path and to partially rotate about an imaginary axis.

9. In a car truck, a bolster, supporting 10 rollers beneath the end portions of said bolster, which rollers are supported upon bearing surfaces curved throughout their length and engage against bearing surfaces on the underside of the bolster, which last 15 mentioned bearing surfaces are curved throughout their length, and said curved bearing surfaces and the rollers are arranged so that the car body when moved laterally from its normal position will be constrained 20 to travel in a curved path and to also partially rotate about an imaginary axis.

10. In a car truck, a bolster, supporting rollers beneath the end portions of said bolster, which rollers are supported upon bearing surfaces curved throughout their length 25 and engage against bearing surfaces on the underside of the bolster, which last mentioned bearing surfaces are curved throughout their length, the bearing surfaces of each pair being oppositely curved, whereby when 30 the car body is moved laterally from its normal position it will be constrained to travel in a curved path and to also partially rotate about an imaginary axis.

In testimony whereof I hereunto affix my 35 signature in the presence of two witnesses, this 14th day of January, 1913.

CHARLES T. WESTLAKE.
